METHOD FOR PRODUCING NAPHTHENES

George D. Kittredge, Bartlesville, Okla., assignor to Phillips Petroleum Company, a corporation of Delaware

No Drawing. Filed July 29, 1957, Ser. No. 674,596

11 Claims. (Cl. 204—162)

This invention relates to a method for producing naphthenes. In one aspect, the invention relates to a method for converting paraffins to naphthenes by exposing the paraffins to high energy gamma radiation. In a particular aspect, the invention relates to a method for converting gasoline boiling range paraffins to naphthenes under the influence of gamma radiation.

During the past several years, the octane requirements of internal combustion engines for passenger automobiles has constantly increased, placing an ever increasing burden upon refiners to develop ways of upgrading low octane fuels to higher octane values. One of the major fields of activity has been the development of better methods of conversion of paraffins to naphthenes, since the naphthenes have a much higher octane value than the paraffins.

It is, therefore, an object of this invention to provide a method for conversion of paraffins to naphthenes. It is another object of the invention to provide processes for improving the antiknock quality of gasoline boiling range paraffins.

Thus, according to the invention, there is provided a process for converting paraffins to naphthenes which comprises irradiation of the paraffins with gamma rays. The process is usually applied to paraffins boiling not over 600° F., although higher boiling paraffins are applicable. The process is especially advantageous as applied to gasoline boiling range paraffins, that is, C₆ paraffins to paraffins boiling up to 400° F. Particularly useful for preparing high octane blending stocks are the paraffins containing 5 to 10 carbon atoms. As feedstocks, the normal paraffins are especially useful since the greatest increase in octane number is obtained starting with the normal paraffins.

An especially advantageous process comprises irradiating gasoline boiling range paraffins and thereby obtaining a reaction product increased in naphthene content, and thereafter subjecting said product of irradiation to a reforming operation to reform the naphthenes to the even higher octane aromatics. In such a process, the feed can contain both normal and isoparaffins, but it is especially advantageous to separate the isoparaffins from the normal paraffins before the irradiation, the isoparaffins already having a quite high antiknock value. The product from the reforming operation can then be blended back with the separated isoparaffins to produce a very high octane blending fuel.

In accordance with the process of the invention, the total dosage of irradiation of gamma rays to which the paraffins are exposed is in the range of 1×10⁷ to 1×10¹⁰ rep. (Roentgen equivalent physical). The rate of exposure to the gamma radiation is generally at the rate of 10³ to 10⁹ rep. per hour, preferably 10⁵ to 10⁸ rep. per hour, although higher or lower rates can be employed.

A wide range of temperatures during the reaction can be employed without any great effect upon the course of the reaction, and temperatures can range from 0° F.

or lower to as high as the thermal cracking temperature of the paraffin being irradiated. Usually temperatures below 300° F. are employed.

Numerous sources of gamma rays for irradiation of the hydrocarbons are available. Such sources as spent fuel elements from nuclear reactors are quite satisfactory and may be very economically used, for these are ordinarily allowed only to deteriorate in activity and then reprocessed for recovery of the fissionable material. By using these spent fuel elements in this process, the radiant energy available as gamma rays is put to use in beneficiating gasoline boiling range hydrocarbons. Other sources of gamma rays, of course, may be utilized, for example, radioactive materials such as cobalt-60 and similar radioactive materials. Any other suitable source of gamma radiation can be used.

The irradiation can, of course, be carried out in either batch or continuous manner, continuous processes ordinarily being preferred because of greater convenience of operation. In either mode of operation, the irradiation is preferably carried out in the absence of oxygen, for the presence of oxygen during irradiation can cause an increase in existent gum. Obviously, such an increase in the gum content of hydrocarbons to be used as motor fuels is undesirable.

The irradiation of paraffins converts at least a portion of the paraffins to naphthenes, and these naphthenes are highly useful as blending materials for spark-ignited internal combustion engines. The upgrading is most effective when the straight chain paraffins are converted to naphthenes, for the greatest increase in octane number is accomplished by this conversion. Obviously, either straight run gasoline or natural gasoline may be used as a source of the paraffins, and it is usually desirable that the straight chain paraffins be first separated from the remainder and the straight chain paraffins then be subjected to irradiation. The irradiated hydrocarbons can then be fractionated to separate the naphthenes and the unconverted paraffins recycled to the irradiation step. The naphthenes so produced can then be blended with the isoparaffins separated from the original gasoline to produce a high performance fuel.

Example I

Separate samples of technical grade normal pentane and technical grade normal hexane were subjected to gamma irradiation from spent fuel elements from the nuclear reactor known as the Materials Testing Reactor, operated for the Atomic Energy Commission, National Reactor Testing Station, Idaho. The samples were irradiated in sealed containers at ambient temperature (about 80° F.). The radiation dosages were about 1×10⁸ rep., employing an average rate of exposure of about 7.5×10⁶ and 6.1×10⁶ rep. per hour for the hexane and the pentane, respectively. Analysis of the charged hydrocarbons and irradiated hydrocarbons are shown in the table:

	Composition, Weight percent			
	Paraffin	Olefin	Naphthene	Aromatic
Normal Hexane:				
Charge	95.0	0.1	0.9	4.0
Irradiated	85.1	1.6	11.1	2.2
Normal Pentane:				
Charge	99.7	0.2	0.1	-----
Irradiated	87.3	1.6	11.1	-----

It is evident from these data that the paraffins were converted to naphthenes in a very substantial amount and with quite high efficiency.

Example II

Several heavy distillate fractions were irradiated as set forth with respect to the irradiation of normal pentane and normal hexane in Example I. In the following table, the compositions of each of three samples are shown both before and after irradiation, the right-hand column in each case being the composition after irradiation.

	Heavy Alkylate	Kerosene	Light Cycle Oil ¹
Boiling Range, ° F.	442-503	348-518	402-535
Paraffins, vol. percent	77.1-61.4	23.6-13.1	16.0-7.3
Naphthenes, vol. percent	17.0-27.0	55.7-61.7	29.5-34.3
Olefins, vol. percent	3.7-9.9	4.9-5.2	19.2-19.3
Aromatics, vol. percent	2.2-1.7	15.8-20.0	35.3-39.0

¹ From catalytic cracking.

All three samples received a total dosage of about 1×10^8 rep. and at an average rate of 7.7×10^6 rep./hr., 7.1×10^6 rep./hr. and 6.1×10^6 rep./hr. for the alkylate, kerosene and cycle oil samples, respectively.

As will be evident to those skilled in the art, various modifications of this invention can be made or followed in the light of the foregoing disclosure and discussion without departing from the spirit or scope of the disclosure or from the scope of the claims.

I claim:

1. A process of producing naphthenes which comprises exposing a paraffin to a total dosage of gamma radiation of 1×10^7 to 1×10^{10} rep. units in the absence of metallic vapors, and thereby forming naphthenes, wherein the said paraffin is a gasoline boiling range paraffin from C_5 paraffins to those boiling up to 400° F.

2. A process of producing naphthenes which comprises exposing a paraffin to a total dosage of gamma radiation of 1×10^7 to 1×10^{10} rep. units in the absence of metallic vapors, and thereby forming naphthenes, wherein the said paraffin contains 5 to 10 carbon atoms per molecule.

3. A process of claim 1 wherein said paraffin is a normal paraffin.

4. A process of claim 1 wherein said paraffin is an isoparaffin.

5. A process for producing naphthenes from paraffins which comprises exposing said paraffins to a total dosage of gamma radiation of 1×10^7 to 1×10^{10} rep. units in

the absence of metallic vapors, at a rate of exposure from 1×10^5 to 1×10^8 rep. per hour, and thereby forming naphthenes, the said paraffins being exposed to gamma radiation being gasoline boiling range paraffins from C_5 paraffins to those boiling up to 400 F.

6. A process for producing naphthenes from paraffins which comprises exposing said paraffins to a total dosage of gamma radiation of 1×10^7 to 1×10^{10} rep. units in the absence of metallic vapors, at a rate of exposure from 1×10^3 to 1×10^9 rep. per hour, and thereby forming naphthenes, the said paraffins being exposed to gamma radiation being gasoline boiling range paraffins from C_5 paraffins to those boiling up to 400° F.

7. Producing naphthenes by exposing a paraffin to gamma radiation and thereby forming said naphthenes, the said paraffins being exposed to gamma radiation being gasoline boiling range paraffins from C_5 paraffins to those boiling up to 400° F.

8. A process of claim 1 wherein the temperature during said exposure is maintained within the range from zero to 300° F.

9. A process which comprises separating isoparaffins and normal paraffins from a gasoline; exposing the normal paraffins to a total dosage of gamma radiation of 1×10^7 to 1×10^{10} rep. units in the absence of metallic vapors, thereby forming naphthenes; reforming said naphthenes to aromatics, and combining said aromatics with said isoparaffins to form a high octane fuel blending stock, the said normal paraffins being exposed to gamma radiation being gasoline boiling range paraffins from C_5 paraffins to those boiling up to 400° F.

10. A process of claim 3 wherein said paraffin is n-hexane.

11. A process of claim 3 wherein said paraffin is n-pentane.
